ELECTRIC CABLE

Gabriel Maria Giannini, Great Neck, N. Y., assignor to Transducer Corporation, New York, N. Y., a corporation of New York

Application May 2, 1939, Serial No. 271,373

3 Claims. (Cl. 174—28)

My invention relates to electric cables and more particularly to flexible coaxial cables for the transmission of high-frequency current.

Although numerous constructions for coaxial cables have been suggested, in general such constructions either do not have the desired degree of flexibility or do not have the desired electrical and mechanical characteristics. More particularly, if the outer hollow conductor is made flexible, for instance of woven wire, and the central conductor is supported therefrom by a plurality of interspaced discs of insulating material, these discs must be spaced very close together in order to prevent the hollow conductor from collapsing. As a result the space between the central conductor and the hollow conductor is for the most part occupied by the discs of insulating material, which, as is well known, does not have the dielectric properties of air.

The main object of my invention is to produce a coaxial cable which is highly flexible and at the same time has excellent electrical properties and retains these properties when it is bent into various shapes.

A further object of my invention is to provide a flexible coaxial cable in which air forms the major part of the insulation between the central conductor and a hollow supporting member which may also serve as a conductor.

A still further object is to provide a cable in which the central conductor is supported in an accurate and simple manner within the hollow supporting member of conductive material.

Another object of the invention is a flexible coaxial cable which may be produced in a simple and inexpensive manner.

A still further object is a cable in which the central conductor can be readily replaced.

A further object is to provide a construction in which the assembly of central conductor, insulators and hollow supporting member can be readily inserted into a stationary tubular outer conductor and withdrawn therefrom.

Further objects and advantages of my novel cable will appear as the description progresses.

In accordance with the invention I use a flexible hollow supporting member in the form of a "reverse spiral" and support the central conductor from this spiral by a plurality of interspaced members of insulating material. This spiral may act as the hollow conductor, or if desired it may be covered by a separate conductor in the form of a flexible metal tube, for instance of woven wire.

The term "reverse spiral" as used herein is to

be understood to mean a hollow body formed by an elongated metal member which extends in one direction over an arc of about 360°, extends axially a short distance, and then reverses its direction and extends in the opposite direction over a similar arc, etc.

In such a "reverse spiral" annular spaces are formed between adjacent turns, and I have found that the insulating discs which serve to support the central conductor can be advantageously supported if their edges fit into these spaces. In addition there is an axially-extending space formed in the "reverse spiral," and by providing the insulating discs with radial grooves it is possible to insert the central conductor after the insulating discs and hollow conductor have been assembled, or to replace the central conductor.

In order that the invention may be clearly understood and readily carried into effect, I shall describe the same in more detail with reference to the accompanying drawing, in which,

Figure 1 is a perspective view, with certain parts removed, of a coaxial cable according to the invention,

Fig. 2 is a front view of one of the insulating discs of Figure 1,

Fig. 3 is a side view of the disc of Figure 2,

Fig. 4 is a side view of an insulating disc according to another embodiment of the invention,

Fig. 5 is a development of the flexible hollow supporting member of Figure 1,

Fig. 6 is a plan view of a flexible support according to another embodiment of the invention, and

Fig. 7 is a development of the support of Fig. 6.

The coaxial cable shown in Figure 1 comprises a flexible hollow supporting member 1 consisting of a metal wire, for instance a steel wire, formed in the shape of a "reverse spiral." As shown at 40 the lower end of the figure, the wire extends counterclockwise over a circular arc of slightly less than 360°, extends in an axial direction a short distance *b*, extends clockwise over a circular arc of slightly less than 360°, and then extends in an axial direction a distance *a*, after which it repeats the cycle. It will be noted that the wire forms annular spaces 2 and also an axially-extending space 3. In practice the distance *a* may be between about one to ten times the diameter of the hollow supporting member. The hollow supporting member 1 is shown in development in Figure 5.

Supported at their peripheries by the adjacent turns of the support forming the annular spaces 2 are a plurality of discs 4 of insulating material,

such as porcelain. Discs 4 are provided with central holes 5 through which extend a central conductor 6 which may be any of the types of wire generally used for this purpose, can be bare or covered, or can be single or stranded.

As more clearly shown in Figures 2 and 3, the discs 4 are provided at their edge with an annular ridge 7 provided with a notch 8. When the discs are assembled in the hollow supporting member 1 (see Figure 1), the ridge 7 fits snugly between adjacent turns of the reverse spiral and the axially-extending portion of the spiral fits into notch 8 to thereby prevent rotation of the discs and hold the discs firmly in the proper position. From Figure 1 it will be noted that the discs 4 can be spaced at a considerable distance apart and the air forms the major portion of the insulation.

Instead of using in the cable of Figure 1, insulating discs of the type shown in Figures 2 and 3, it is possible to use discs 10 such as shown in Figure 4. The disc 10 is the same as the disc 4 shown in Figures 2 and 3 except that it is provided with a notch 16 and a radially-extending slot 11, whose sides are at an angle to the axis of the central hole 12. When such discs are used in Fig. 1 it is possible to insert the conductor 6 through the axially-extending space 3 and slots 11 into the central hole 12 in the discs. Due to the angle of the slots 11, the conductor will be retained with the central hole.

If the distance *a* and *b* are made small the hollow supporting member 1 may also serve as the outer conductor, in which case the sheath 9 may be made of insulating material such as woven fabric. However, as shown in Figure 1, the hollow supporting member 1 is surrounded by a flexible sheath 9 of woven wire.

Instead of forming the hollow supporting member 1 from wire it may be stamped from metal and such a construction is illustrated in Figures 6 and 7. As shown in Figure 7, a flat member 15 of serpentine shape is stamped from a sheet of metal. This metal is then bent into a tubular shape, as shown in Figure 6, which serves as the hollow supporting member.

While I have described my invention with reference to certain applications and specific structural details, I do not wish to be limited thereto because obvious modifications will readily occur to one skilled in this art.

What I claim is:

1. A flexible cable comprising a hollow supporting member formed of an elongated metal member, said supporting member having a plurality of similar portions each formed by said metal member extending clockwise over a circular arc of approximately 360°, extending axially a short distance, extending counterclockwise over a circular arc of approximately 360° and then extending axially a short distance, a conductor within said hollow member, and a plurality of interspaced members of insulating material supported by the circular arc portions of said hollow member and supporting said conductor.

2. A flexible cable comprising a hollow supporting member formed of an elongated metal member, said supporting member having a plurality of similar portions each formed by said metal member extending clockwise over a circular arc of approximately 360°, extending axially a short distance, extending counterclockwise over a circular arc of approximately 360° and then extending axially a short distance, a conductor within said hollow member, and a plurality of interspaced discs of insulating material supported by said hollow member and supporting said conductor, each of said discs having a peripheral ridge fitting between adjacent circular portions of said metal member.

3. A flexible cable comprising a hollow supporting member formed of an elongated metal member, said supporting member having a plurality of similar portions each formed by said metal member extending clockwise over a circular arc of approximately 360°, extending axially a short distance, extending counterclockwise over a circular arc of approximately 360° and then extending axially a short distance, a conductor extending through the central part of said supporting member, and a plurality of discs of insulating material supporting said conductor from said supporting member, each of said discs having a peripheral portion fitting between adjacent circular portions of the metal member and provided with a transverse notch engaged by an axially-extending portion of the metal member.

GABRIEL M. GIANNINI.
